UNITED STATES PATENT OFFICE.

LUTHER W. HOLLAND, OF PLEASANT HILL, MISSOURI, ASSIGNOR TO HOLLAND AUTOMATIC LOCK CO., OF PLEASANT HILL, MISSOURI, A CORPORATION OF MISSOURI.

LATCH.

1,221,180.

Specification of Letters Patent.

Patented Apr. 3, 1917.

Application filed June 2, 1916. Serial No. 101,348.

To all whom it may concern:

Be it known that I, LUTHER W. HOLLAND, a citizen of the United States, and a resident of Pleasant Hill, in the county of Cass and State of Missouri, have invented a new and useful Improvement in Latches, of which the following is a specification.

My invention relates to improvements in latches and it consists in the combinations, 10 constructions and arrangements herein described and claimed.

An object of my invention is to provide a latch having a detent which engages a strike-plate so as to release the latch-bolt and 15 permit the latter to move forwardly into locking position, said latch-bolt and said detent being operated by a single spring.

A further object of my invention is to provide a latch of the type described which 20 is made of few parts and which is, therefore, not easily liable to get out of order.

A further object of my invention is to provide a latch to be used on automobile doors or the like which may be readily operated to release the door either by means of 25 a knob or by a lever or both.

Other objects and advantages will appear in the following specification and the novel features of the device will be particularly 30 pointed out in the appended claims.

My invention is illustrated in the accompanying drawing, forming part of this application, in which—

Figure 1 is a side view of a lock,

Fig. 2 is a plan view,

Fig. 3 is a perspective view of the detent,

Fig. 4 is a face view of the lever, and

Fig. 5 is a section on the line 5—5 of Fig. 1.

In carrying out my invention I provide a 40 plate 1 of sheet metal which forms the base or support of the movable parts. This plate 1 is bent at its forward end to form a flange 2, a portion 3 being stamped from the plate 2, and bent rearwardly so as to leave a bolt-opening.

Near the rear end of the plate two ears 4 and 5 respectively are stamped from the plate and bent up to form supports for the pivot pin 6 of a detent 7 like that shown in Fig. 3. This detent, it will be observed, is provided with an opening 7^a arranged to receive the pin 6 and has an extension 7^b at right angles to the main body portion, this extension being provided with a lug 7^c. The

opposite end of the detent is bent laterally to form an engaging portion 7^d, while at 7^e are one or more teeth. The latch-bolt 8 is formed of a single piece of metal which is bent at the forward end of the bolt as 60 shown at 8^a in the form of a cam-curve or bevel and extends rearwardly in a direction parallel to the main body portion as shown in Fig. 2, being bent laterally toward the main body portion to form a stop member 65 8^b. As will be seen from Fig. 1 the bolt has a lateral extension 8^c provided with ears 8^d arranged to partly encircle a lever or handle 9 whose end is rounded as shown at 9^a to fit in an arc-shaped guide 70 member 10 which may be struck up from the sheet 1. The latch-bolt 8 passes between the plate 1 and the pin 6 and the pin is shown in Fig. 1. The lever 9 is provided with a squared opening 9^b near 75 the rounded end 9^a through which the squared shank of a knob may extend. It is also provided with a lug 9^c on one side and with a notch 9^d on the other side contiguous to which is a flange 9^e.

At 11 the plate is cut away to provide room for a spiral spring 12, one end of which fits over the lug 7^c of the detent and the other end of which fits over the lug 9^c on the lever 9 and bears against the lever. 85

The operation of the lock will be readily understood.

It is designed to be used in connection with a strike-plate 13 which may be secured to the jamb of the door and which is provided with an opening to receive the bolt 8. Figs. 1 and 2 show the bolt in a retracted position. It will be noted that in this position the spring 12 is compressed. This tends to force the end 7^d of the detent 90 through the plate 1, the position of the detent depending upon the engagement of the latter at the teeth 7^e with the stop member 8^b of the bolt. This prevents the bolt from springing forward under the action of the spring 12, for it will be observed that the spring 12 tends to force the lever 9 forwardly and hence also the bolt 8, through the engagement of the lever by the extension which bears the ears 8^d. Now when the 100 door is closed, the end 7^d of the detent engages the strike-plate which forces the detent inwardly, the opposite end of the detent tending to compress the spring 12 to a greater extent. As soon as the stop 8^b is 105 110

2
free, the lever and the bolt 8 will spring forwardly into locking position. The mere reversal of the lever will cause the bolt to be retracted and will force the forward end 5 of the detent in behind the stop member 8 as the latter moves rearwardly. I have shown three teeth on the detent so that the bolt may be engaged at three different positions, but it is obvious that more or less 10 number of teeth might be used without departing from the spirit of the invention.

It will be observed that the pin 6 not only 15 serves as a pivot pin for the detent, but that this same pin also serves as a guide member 15 for the bolt. It will also be observed that the portion 3 which is struck from the plate 1 to provide an opening for the bolt serves as the forward guide member of the bolt.

20 I claim:—

1. A latch comprising a base plate having an opening, a U-shaped detent having one end arranged to extend through the opening, a spring having one end engaging the opposite end of the U-shaped detent, a lever having one end pivotally mounted on said base plate and being pressed upon by the opposite end of said spring and a latch-bolt having a portion arranged to be engaged by said detent, and being loosely connected with said lever so as to move with the latter.

2. In a latch, a base plate having a laterally extending flange at one end provided 35 with a lip punched from the flange to provide a bolt opening, said lip being bent into a plane parallel with the body portion of the plate and constituting a guide member, 40 a U-shaped detent, a pivot pin for said detent carried by the plate and spaced therefrom, one end of said bolt passing between the pin and the plate, means carried by the

bolt and arranged to be engaged by the detent for normally preventing the forward movement of the bolt, a lever having one 45 end pivotally mounted on said base plate and being loosely connected with the bolt and a spiral spring arranged to bear at one end on said lever and at the other end on said U-shaped detent. 50

3. In a latch, a base plate having a pair of ears stamped therefrom and bent at right angles thereto to form a bearing, a pivot pin arranged to extend through the bearing, a detent pivotally mounted on said pivot pin, a lever pivotally mounted at one end on said base plate, a latch-bolt extending between said pivot pin and said base plate, said latch-bolt having a portion arranged to be engaged by said detent, a spiral spring 60 disposed between said detent and said lever, one end of said detent being arranged to extend normally through the base plate.

4. In a latch, a latch-bolt consisting of a single piece of metal bent at one end to form a cam-curve or bevel and being provided with a bent portion constituting a stop member, a base plate having a pair of ears struck up therefrom, a pivot pin carried by said ears and forming a guide for said bolt, a detent pivotally mounted on said pivot pin and arranged to extend normally through the base plate, a lever having one end pivotally mounted on said base plate, an extension carried by the bolt and arranged to loosely engage the lever, and a spiral spring having one end engaging the lever and the opposite end engaging the detent. 70 75
